UNITED STATES PATENT OFFICE.

WILLIAM E. ANDRÉ, OF CHICAGO, ILLINOIS, ASSIGNOR, BY MESNE ASSIGNMENTS, TO THE AMERICAN LAUNDRY MACHINERY MANUFACTURING COMPANY, A CORPORATION OF NEW JERSEY.

BOSOM-BOARD FOR IRONING-MACHINES.

No. 868,959.

Specification of Letters Patent.

Patented Oct. 22, 1907.

Application filed November 2, 1905. Serial No. 285,594.

To all whom it may concern:

Be it known that I, WILLIAM E. ANDRÉ, a citizen of the United States, and a resident of Chicago, county of Cook, and State of Illinois, have invented certain

5 new and useful Improvements in Bosom-Boards for Ironing-Machines, of which the following is a specification, and which are illustrated in the accompanying drawings, forming a part thereof.

10 The invention relates to bosom boards or ironing tables adapted for use in connection with ironing machines of the type shown in my pending application Serial No. 262,562, filed May 27, 1905; and its object is to simplify and improve the mechanism for securing a shirt bosom upon the board.

15 The invention consists in the device as hereinafter described, and as illustrated in the accompanying drawings, in which—

20 Figure 1 is a side elevation of the board, its shield being shown in longitudinal section; Fig. 2 is a plan view, the bosom-holding mechanism being shown as retracted and some of the parts being shown in dotted lines; Fig. 3 is a plan view, the bosom-holding mechanism being shown as closed; Fig. 4 is a transverse section on the line 4—4 of Fig. 3 some parts being omitted to 25 avoid confusion; and Figs. 5 and 6 are details of certain parts of the neck and shoulder clamping devices.

25 The board is shown as provided with a substantial base 10, taking the form of a saddle 11 adapted to ride upon a carrying arm 12 of the ironing machine. The 30 board 13 is, as usual, provided with a cover 14, in the present instance being clamped thereto by means of a band 15. A semi-circular plate 16 is secured at one end of the board and has an upstanding flange or band 17 over which the neckband of a shirt may be drawn.

35 A pair of spreading arms 18, 19, are mounted below the board, each being provided with an upstanding stud 20, 21, at its outer end for projecting into the neckband of the shirt, these arms being arranged to move so as to stretch the band transversely. A pair of clamping blocks 22, 23, are mounted upon swinging arms 24, 25, pivoted to the base 10 or, preferably as shown, to a bracket 26 projecting from the end of the base so as to 40 permit the clamping blocks to swing against the end of the board, as shown in Fig. 3. A pair of clamping 45 jaws 27, 28, are mounted at the opposite end of the board, and are openable to receive the skirt of the garment and movable away from the board to stretch it.

50 The neck-engaging band 17 is centrally recessed, as shown at 29, for the engagement of a button inserted in the front of the neckband of the shirt. A binding plate 30, carried by a swinging arm 31 pivoted to the board or to the extension bracket 26 thereof, is adapted to fold over upon the neck-engaging band and has a 55 depending flange 32 for clamping the neckband of the shirt thereto, this flange being recessed, as shown at

33, to receive the shank of the collar button. A post 34 rises from the board 13 within the neck-engaging band 17, and has a forwardly projecting bill 35 at its upper end.

60 The plate 30 is slotted, as shown at 36, to receive the post 34, and after being thrown over upon the neck-engaging band the plate is drawn backwardly to bring it under the bill 35, thereby locking it in position. This retraction of the plate 30 is accomplished by means of an eccentric 37, carried by the arm 31 and 65 upon which the arm 30 is pivoted, the eccentric being provided with a handle 38 by means of which it may be turned. The arm 31 or the bracket 26 may be slightly flexible and elastic so as to yield to the action of the eccentric should the parts not be accurately 70 proportioned. The arm 31 is preferably provided at its lower end with a pair of laterally projecting feet 39, 40, so disposed as to allow it but a limited range of movement upon its pivot.

75 The rods 18, 19, slide in suitable clips 41, 42, secured to the under side of the board 13, and are curved so that as they are advanced the studs 20, 21 are spread relatively. Each of the rods 18, 19, carries a coiled advancing spring 43, and the rods are retracted by means of a sliding cam 44, acting upon a crank-arm 45, 80 fixed to a shaft 46 journaled in the base of the device and carrying crank-arms 47, each of which is connected by means of a link 48 with one of the rods.

85 The clamping blocks 22, 23 are controlled by means of a shaft 49, journaled in the base 10 and having a hand-crank 50 and crank-arm 51, the latter being connected by means of a link 52 with a cross-bar 53, uniting the arms 24, 25. In order that the blocks 22, 23 may engage the garment with a yielding pressure, the link 52 is connected with the cross-arm 53 by means 90 of a spring 54 housed within a box 55, secured to the cross-arm, and through which the link slides, the spring being coiled about the link and reacting between the forward end of the box and a nut 56 on the end of the link.

95 The clamping jaws 27, 28 are mounted on rods 57, 58, sliding in clips 59, 60, secured to the under side of the board, the outer jaw 28 being fixed upon the ends of the rods and the inner jaw 27 being slidable upon the rods and advanced towards its companion by means 100 of springs 61, 62, coiled about the rods 57, 58, and reacting between the jaw and bosses 63, 64, mounted upon the rods. Preferably the garment is secured between the jaws by means of a bar 65, the garment being first laid across the jaws when open and the bar 105 being inserted to fold it between them and being secured between the jaws, as shown in Fig. 3. The rods 57, 58, also carry springs 66, 67, reacting between suitable bosses 68, 69, on the rods and the inner clips 59, and serving to extend the rods for the purpose of stretch- 110

ing the garment when secured between the clamping jaws. These clamping jaws are controlled by means of a cam 70, acting upon a bell-crank 71, which is connected by means of a link 72 with the inner jaw 27.

5 The two cams 44 and 70 are preferably formed on a slide-block 73, running on suitable ways 74, as shown comprising a rib formed on the base of the device, the block having a longitudinal slot through which there is set into the side of the base a headed bolt 80 for retaining the block in its place on the rib. The cam-block is controlled by means of a hand lever 75, fixed upon a shaft 76 journaled in the base and having a crank arm 77, attached by means of a link 78 to the slide-block.

10 15 The cams and the crank-arms co-operating therewith are so disposed that when the lever 75 is brought to an upright position, as shown in Fig. 1, the rods 18, 19, are retracted and the clamping jaws 27, 28, are drawn in towards the end of the board and are separated.

20 25 In mounting a garment upon the board the neckband is first adjusted to the band 17, when the studs 20, 21, are spread to stretch it, by throwing the hand lever 75 a short distance to the left, thereby moving the cam-block 73 to the right and allowing the crank-arm 45 to slide down the inclined cam 44, permitting the springs 43 to expand. The plate 30 is now adjusted in position and the clamping blocks 22, 23, are advanced to grip the shoulders of the garment.

30 The skirt of the garment being spread over the clamping jaws 27, 28, the bar 65 is applied to force it between the jaws, and the hand lever 75 being now moved still farther to the left the bell-crank 71 slides down the inclined cam face 70, first permitting the jaw 27 to advance to grip the garment and then allowing the pair of jaws to be extended under the influence of the springs 66, 67, to stretch the garment. The springs 61 and 62 should be of slightly greater tension than the springs 66, 67, so that the latter are the first to compress but last to expand.

35 40 45 The cams 44 and 70 are so related that the former is brought into action to relieve the springs 43 before the latter relieves the springs of the clamping jaws. The board is provided with the usual shield or tray 79 to prevent the sleeves and skirt of the garment from hanging down and becoming soiled by the machinery.

I claim as my invention—

1. In combination, an ironing board having a neckband engaging flange, a pair of spring-advanced reciprocable rods mounted below the board to move in diverging paths, each rod carrying a neck-band engaging stud, and means 50 for retracting the rods.

2. In combination, an ironing board having a neckband engaging flange, a pair of spring-advanced reciprocable rods mounted below the board to move in diverging paths, each rod carrying a neckband engaging stud, a rocking 55 crank-shaft, and link connection between the rods and crank shaft.

3. In an ironing board, in combination, a board having a neckband engaging flange, a pair of studs arranged to enter a neckband when engaged by the flange, a pair of oppositely curved spring-advanced slidable rods carrying the studs, a crank shaft, connections between two of the cranks of the shaft and the arms, and a cam acting on one of the cranks of the shaft to rock the shaft in opposition to the rod springs. 60

4. In an ironing board, in combination, a board having a neckband engaging flange, means independent of the flange, for stretching a neckband when engaged thereby, and clamping blocks movable into engagement with the end of the board. 65

5. In an ironing board, in combination, a board having a neckband engaging flange, means independent of the flange, for stretching a neckband when engaged thereby, and clamping blocks yieldingly engaging the end of the board. 70

6. In an ironing board, in combination, a board having a neckband engaging flange, means for stretching a neckband when engaged by the flange, oscillatable clamping blocks movable against the end of the board, a crank shaft, and link connection between the shaft and the blocks. 75

7. In an ironing board, in combination, a board having a neckband engaging flange, means independent of the flange, for stretching a neckband when engaged by the flange, oscillatable clamping blocks movable against the end of the board, a crank shaft, and link yieldingly connecting the crank of the shaft with the blocks. 80

8. In an ironing board, in combination, a board, spring-advanced spreading studs for engaging the neckband of a garment, spring-extended clamping jaws movable towards and away from the board, a rocking crank shaft operatively connected with the studs, a rocking crank shaft operatively connected with the jaws, a double cam for actuating the rocking shafts successively, a crank shaft, connection between the crank of such last-named shaft and the cam, and a hand lever mounted on the last-named shaft. 85 90
